LIP GUARD

Charles Swartz, New York, N. Y.

Application May 16, 1934, Serial No. 725,986

3 Claims. (Cl. 2—174)

The present invention relates to new and useful improvements in lip guards for use particularly by women in clothing establishments, and has for its primary object to prevent the discoloration of dresses and other garments by rouge on the lips when said dresses or other garments are being put on or removed.

Other objects of the invention are to provide a lip guard of the aforementioned character which will be comparatively simple in construction, highly efficient and reliable in use, sanitary, and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

20 Figure 1 is a front perspective view, showing a lip guard in accordance with the present invention in use.

Figure 2 is a view in front elevation of the lip guard.

25 Figure 3 is a plan view of the invention, showing the same when not in use.

Figure 4 is a plan view, showing the parts of the device in the position which they assume when in use.

30 Figure 5 is a sectional view, taken substantially on the line 5—5 of Figure 4.

Referring now to the drawing in detail, it will be seen that the embodiment of the invention which has been illustrated comprises a shield 1 of suitable material, preferably heavy paper. As illustrated to advantage in Figures 1 and 2 of the drawing, the shield 1 conforms substantially in outline to the outline of the human lips.

The shield 1 is of flexible material and struck longitudinally therefrom is a retaining or supporting bit 2 for engagement between the lips or teeth of the user for maintaining said shield 1 in position. The bit 2 terminates in enlarged or flared end portions 3 which merge with the shield 1.

It is believed that the manner of using the device will be readily apparent. The bit 2 is flexed laterally in a manner to project from the shield 1 to permit said bit to be conveniently gripped between the lips or teeth of the user. In this manner the shield 1 will be held firmly in position over the lips of the user for protecting garments which are being put on or removed, as suggested in Figure 1 of the drawing. It will be noted that the article is formed from a single sheet of material and, being of paper, will be very inexpensive and may be discarded after use by one person. The enlarged end portions 3 provide strong joints between the bit 2 and the shield 1. When the bit 2 is drawn between the lips of the user, the shield 1 is bowed longitudinally in a manner to conform to the curvature of the lips, as best seen in Figure 4 of the drawing.

It is believed that the many advantages of a lip guard constructed in accordance with the present invention will be readily understood, and although a preferred embodiment of the invention is as illustrated and described, it is to be understood that changes in the details of construction may be resorted to which will fall within the scope of the invention as claimed.

What is claimed is:

1. A lip guard of the class described comprising a substantially flat, resilient shield, and a bit struck from the shield for engagement between the lips, said bit including enlarged end portions merging with the shield.

2. A lip guard comprising a shield of flexible material, said shield having slits therein, the area between said slits constituting a flexible tongue adapted to be bent outwardly for engagement between the lips.

3. A lip guard comprising a flexible shield, said shield having spaced, substantially parallel slits therein terminating, at their ends, in spaced relation to the marginal edges of the shield, the area between said slits constituting a bit for engagement between the lips.
